UNITED STATES PATENT OFFICE.

JOSEPH A. POITRAS, OF NEW YORK, N. Y.

DIVIDING HEAD.

Application filed February 26, 1921. Serial No. 448,218.

To all whom it may concern:

Be it known that I, JOSEPH A. POITRAS, a citizen of the United States, and resident of the borough and county of the Bronx, 5 city and State of New York, have invented certain new and useful Improvements in Dividing Heads, of which the following is a specification.

My invention relates to dividing heads and 10 has for its object to provide a mechanism of this type of simple construction and efficient operation whereby the operation of dividing a circle into predetermined divisions is reduced to the utmost simplicity. Another 15 purpose of my invention is to provide a dividing head adapted more particularly for use in combination with milling machines and the like to successively adjust the work for equal division as is required, for in- 20 stance, in various forms of graduating operations, gear cutting and the like. Other more specific objects of my invention will appear from the description hereinafter, and the features of novelty will be pointed 25 out in the appended claims.

Reference is to be had to the accompanying drawings which illustrate a specific embodiment of my invention without defining its limits and in which Figure 1 is a side 30 elevation of the dividing head; Fig. 2 is an end elevation thereof; Fig. 3 is a sectional elevation on the line 3—3 of Fig. 4; Fig. 4 is a sectional view on the line 4—4 of Fig. 3; Fig. 5 is a sectional view on the line 35 5—5 of Fig. 1; Fig. 6 is a detail face view of the index plate; Fig. 7 is a sectional view thereof on the line 7—7 of Fig. 6; Fig. 8 is a detail view of the locating arm which forms part of the mechanism; Fig. 9 is a 40 sectional view thereof on the line 9—9 of Fig. 8; Fig. 10 is a detail view of a trigger which forms part of the construction; Fig. 45 11 is a detail view of a tripping device included therein; Fig. 12 is a fragmentary sectional view on the line 12—12 of Fig. 11; Fig. 13 is a fragmentary sectional elevation on the line 13—13 of Fig. 14 showing another form of my dividing head; Fig. 14 is an end elevation thereof and Figs. 15, 50 16 and 17 are detail views of the form shown in Figs. 13 and 14.

As shown in the illustrated examples, the dividing head comprises a head-stock casting consisting of a base 15 and an upright 55 standard 16 which terminates in a bearing

17 in which a hollow shaft or spindle 18 is journalled. The latter is held against lengthwise movement relatively to the bearing 17 by means of an annular flange 19 preferably forming an integral part of said 60 shaft 18 and one or more spindle nuts 20 screwed upon said shaft, said spindle nuts, for instance, being split and fixed in place by means of screws 20^a, as shown in Fig. 4, or being replaced by a pair of collars 20 65 as illustrated in Fig. 13. Any suitable means may be provided for securing the work or blank which is to be divided in co-operative connection with the shaft 18, the character of this means being determined 70 by the work for which the dividing head is constructed; for instance, the chuck shown in the illustrated example may be utilized for this purpose. This chuck comprises a tube 21 longitudinally split at intervals, as indicated at 22, to form terminal gripping jaws 23 having an inherent resiliency tending to expand the same, said jaws being provided with inclined surfaces 24 co-operating with similar surfaces 25 of the 80 shaft 18 to actuate said jaws, as will appear more fully hereinafter. A stud 26 carried by the shaft 18 projects into a key-way 27 formed on the outer periphery of the tube 21 and serves to secure said tube and with 85 it the gripping jaws to the shaft 18 without interfering with the necessary lengthwise movements of said tube and jaws relatively to said shaft. For the purpose of operating the jaws, the inner end of the tube is 90 externally screw-threaded for engagement with the internally screw-threaded end of a draw tube 28 which extends lengthwise of the shaft 18 and projects beyond the one end thereof, as shown in Fig. 4. The projecting end of said draw tube 28 carries an actuating means which, in the illustrated example, is shown in the form of an operating knob 29, the periphery of which is preferably knurled and provided at spaced 100 intervals with recesses 30 for the accommodation of a suitable tool whereby manipulation of said knob is facilitated. The knob 29 is fixed upon the draw tube 28, for instance, by means of an annular flange 31 105 formed thereon and a pin 32 which projects through the hub of the knob 29 into the draw tube 28, as illustrated in Fig. 4. It will be understood that the type of chuck mechanism shown in the drawings has been 110

chosen for illustrative purposes and therefore may be replaced by any other means or devices suitable to the purposes for which any particular dividing head is designed.

5 The shaft 18 has fixed thereon a carrier which, as shown, may comprise a split collar 33 secured in position, for instance, by means of a bolt 34 and provided with a clamp 35 in which an arm 36 is adjustably secured, for instance, by means of a bolt 37. At its outer end, the arm 36 is formed with a recessed bearing 38 which extends transversely to the arm and accommodates a locating pin 39 provided with an operating 10 knob 40 and maintained in and returned to its operative position by means of a spring 41. In the form shown in Figs. 1, 2, 3 and 4, an index plate 42, preferably of circular form, is loosely mounted on the 15 shaft 18 and is provided with recesses or apertures 43^a arranged in series *a*, *b*, *c*, *d*, *e*, *f*, *g* and *h* in the arcs of circles each of which has a different radius from all of the others, said apertures being adapted to 20 receive the end of the locating pin for the purpose to be more fully described hereinafter. The index plate 42 is preferably formed on its periphery with teeth 43 adapted for co-operation with a locking device whereby said index plate is fixed against rotation, said locking device comprising a latch pin 44 slidably mounted in a housing 45 secured upon the base 15 in any suitable manner, as by means of bolts 25 46, said latch pin being held against turning in said housing and in proper operative relation to the teeth 43 by means of a key 44^a and being controlled through the medium of a spring 47; the latch pin is further provided with a shoulder 48, as shown 30 in Fig. 4. A trigger 49 is pivotally mounted upon the housing 45 and by co-operating with the shoulder 48 is arranged to maintain the latch pin 44 in an inoperative position; the trigger 49 is yieldingly pressed 35 toward the latch pin 44 by means of a spring 49^a and projects beyond the housing 45 into the path of a tripping member 50 adjustably mounted by means of screws 51 and a 40 block 52 in a groove 53 extending circumferentially about the periphery of an index actuating member 54. In the form shown in Figs. 1 to 4 inclusive, the latter is loosely mounted upon the shaft 18 so as to rotate 45 relatively thereto and is recessed on its one face as indicated at 55 in Fig. 3. The member 54 carries a lift cam 56 which is pivoted thereto at 57 and is arranged, in the operation of the mechanism, to depress the latch 50 pin 44 to the position shown in Fig. 3 in which said latch pin is disengaged from the teeth 43. The lift cam 56 is held against pivotal movement relatively to the member 54 in one direction by means of a pin 55 58 on said member 54, and is free to pivot-

ally swing in the opposite direction, as is clearly shown in Figs. 2 and 3; a spring 59 serves to return said lift cam to its normal position and to maintain it therein. A toothed pawl 60 is pivotally mounted at 61 upon the member 54 within the recess 55 and in surface contact with the face thereof, and in one of its positions abuts against a pin 62 projecting outwardly from the member 54 or, more specifically, from the face of the recess 55 thereof, as shown in Fig. 3. The pawl 60 co-operates with a ratchet wheel 63 which is fixed upon the shaft 18 between the member 54 and the spindle nut 20, as illustrated in Fig. 4. The member 54 is further provided with a projection or stud 64 which co-operates with a stop 65 fixed upon the standard 16 to pre-determine the initial position of the apparatus. To facilitate the operation of the mechanism, the member 54 may be provided with an operating handle 66.

For the purpose of simplifying the description of the operation of the dividing head, I have chosen the cutting of teeth upon a suitable circular blank or, in other words, the cutting of a gear as an example of how the dividing head may be utilized to divide a circle into predetermined divisions; it will be understood that this is in no sense to be taken as defining the limits of the invention.

In practice, in such case, the blank upon which the gear teeth are to be cut is mounted upon the shaft 18, for instance through the medium of the gripping jaws 23, the latter being first opened by manipulating the knob 29 in one direction and thereby rotating the draw tube 28 relatively to the tube 21 to cause the latter to move outwardly with respect to the shaft 18 and then adjusted into gripping relation with the blank by actuating the knob 29 in the reverse direction to cause the tube and with it the gripping jaws to be drawn inwardly relatively to said shaft 18. It will be understood that as the tube 21 is moved outwardly, the inherent resiliency of the material of which the jaws are constructed will cause the latter to expand while the camming action of the surfaces 24 and 25 will adjust said jaws 23 to their gripping position as the tube 21 is moved inwardly. For the purposes of explanation, it will be assumed that it is desired to cut one hundred teeth upon the periphery of the blank in question, it being understood that the parts, as illustrated in Figs. 1 to 4 inclusive, occupy a normal position in which the stud 64 is in contact with the stop 65 and the latch pin 44 is in engagement with the teeth 43 of the index plate 42 which is thus held against rotation. To bring the proposed result about, the arm 36, if not already in such position, is first adjusted in the clamp

35 of the carrier 33 and, if necessary, swung in the arc of a circle, to bring the locating pin 39 into registry with and into the first aperture 43^a of the series *a*; in the form being described, the rotary adjustments of the arm 36 are communicated to the shaft 18 and to the work carried thereby, and thus adjust the latter relatively to the milling machine which may be of any well known type and has not been illustrated as it forms no part of the present invention. At this time or previously thereto, the tripping member 50 is adjusted in the groove 53 to a position in registry with the fourth 15 tooth 43 from the cam 56 or, in other words, to a position in which three teeth 43 are between the tripping member 50 and said cam 56, as shown in Figs. 2 and 3. In this position, the index plate 42 is coupled to the 20 shaft 18 through the medium of the index pin 39 and arm 36. The handle 66 may now be operated to rotatably actuate the member 54 to the left in Fig. 3, thereby carrying with it the pawl 60 and the cam 56. The 25 pawl 60 is so arranged with respect to the ratchet wheel 63 that it does not come into actual coupling relation thereto until the cam 56 has reached the position indicated in Fig. 3, in which the latch pin 44 is depressed 30 out of engagement with the teeth 43 and locked in this position by means of the trigger 49; in other words, the member 54 is capable of a predetermined, initial movement independent of the shaft 18, to bring 35 about these results. This is due to the fact that, during the movement of the handle 66 and member 54 from the position shown in Fig. 2 to that illustrated in Fig. 3, the pawl 60 lags behind, as it were, or, in other words, 40 rolls along the teeth of the ratchet wheel 63 until it finally engages the pin 62 and, being held thereby against further relative movement, couples the member 54 and the ratchet wheel 63 together. A continued 45 movement of the handle 66 in the indicated direction will now cause the ratchet wheel 63 to move with the member 54 and to communicate its motion to the shaft 18 and to the arm 36 which in turn, through the medium of the pin 39, rotatably moves the index plate 42. The described movement continues until the tripping member 50 engages the trigger 49 and trips the same to release the latch pin 44 and permit it to again engage the teeth 43 of the index plate 42. The 50 blank is thus locked in position for cutting a tooth, which having been accomplished, the handle 66 is actuated in a reverse direction or to the right in Fig. 3, thereby similarly moving the member 54. In this direction of movement, the pawl 60 travels over the teeth of the ratchet 63 without actuating said ratchet, while the cam passes over the latch pin 44 without depressing the 55 same, said cam 56, as before stated, being

free to move in this direction. At the same time, the tripping member 50 is moved in a direction away from the latch pin 44, the parts assuming the position indicated in Fig. 2. In other words, in this operation of the mechanism, the movement of the elements 54, 60, 56 and 50 is relative to the ratchet 63, the index plate 42, the arm 36 and the shaft 18 with its co-related parts, so that the blank does not partake of this return movement. 70 Another actuation of the handle 66 to the left in Fig. 3 will again operate the parts as previously described, and will thus rotatably advance the blank a distance corresponding to the distance between four teeth, 80 thus bringing the blank to this new position in which a second tooth is cut, this second tooth corresponding, in the finished gear, to the fifth tooth from the one first cut. These operations of the handle 66 are continued 85 alternately five times in the example chosen for the purposes of illustration, whereby a complete rotation of the blank has been accomplished and twenty teeth have been cut thereon or said work has been adjusted 90 to twenty successive positions for different dividing purposes. At this stage, the locating pin 39 is withdrawn from the first aperture 95 of this series. This causes a corresponding movement of the arm 36 and shaft 18 and rotatably moves the blank to a similar degree which corresponds to the space between two adjacent teeth. The same operations 100 hereinbefore set forth are now proceeded with, with the result that the blank is successively positioned so that twenty additional teeth or other divisions may be cut or produced upon the blank contiguous to and 105 between the twenty teeth cut or the divisions produced during the first operation. The pin 39 is thereupon adjusted to the third aperture of the series *a* and subsequently, at the proper times, to the fourth and fifth 110 apertures thereof, the parts being operated at each time to adjust the blank to a position in which a new tooth is cut or a new division is produced in proper relation to the preceding teeth or divisions. If a hundred 115 teeth are being cut or the same number of divisions are required, the operation provides for the adjusting of the blank to five different positions, in each of which twenty teeth or divisions are cut or produced. 120 To cut ninety teeth upon the blank or to divide the same into ninety divisions for other purposes, the arm 36 is adjusted in its carrier 35 to move the locating pin 39 inwardly into registry with the apertures 43^a 125 of the series *b*, after which the operations hereinbefore described are proceeded with. Thus, by bringing the pin 39 into registry with the various series of apertures, it is possible to accurately position the blank 130

either with respect to a cutting mechanism or with other devices for the purpose of cutting any desired number of teeth on the periphery thereof or for dividing said blank 5 into divisions for any other purpose.

In the form illustrated in Figs. 13 to 17 inclusive, the index plate 42^a is mounted upon a hub with which the ratchet 63^a is provided in this arrangement; the index plate 42^a and the ratchet 63^a are fastened together by means of screws 42^b to move in unison, as illustrated in Fig. 13. It will be understood that the index plate 42^a corresponds to the index plate 42 of the form 10 first described and likewise may be formed with a plurality of recesses or apertures 43^a similarly arranged in series *a*, *b*, *c*, *d*, *e*, *f*, *g* and *h*, these apertures or recesses cooperating in the same way with the locating pin 15 39 to adjust the mechanism, and having been omitted from Fig. 14 simply to avoid a confusion of lines therein. With this arrangement, the ratchet 63^a which corresponds to the ratchet 63 of the first form 20 and the connected index plate 42^a are loosely mounted upon the hollow spindle 18. In the form now being described, the index actuating member 54^a, instead of being loosely mounted upon the spindle 18 as is 25 the member 54 in the first form, is loosely mounted upon the previously mentioned hub of the ratchet 63^a. In the present instance, this index actuating member 54^a is provided on its one face with undercut annular 30 grooves in which internally screw-threaded sleeves 54^b are located, said sleeves projecting into co-operating recesses formed in an auxiliary member 54^c which lies in surface engagement with the member 54^a and is secured in fixed relation thereto or 35 released therefrom through the medium of screws 54^d which screw into the sleeves 54^b; as shown in Fig. 13, the auxiliary member 54^c and the member 54^a together form what 40 may be termed a two-part actuating member, the purpose of which will appear more fully hereinafter. For convenience of operation, the screws 54^d may be constructed 45 with heads provided with apertures 54^e adapted to receive and accommodate a suitable tool. The index actuating member 54^a carries the lift cam 56 whereby the latch pin 44 is depressed in the operation of the mechanism in the same manner as hereinbefore 50 described. As a substitute for the projection or stud 64 of the first form, the arrangement at present being described includes a stop 64^a carried by the auxiliary member 54^c and arranged to abut against 55 the housing 45 as will be more fully described hereinafter, instead of against the stop 65, as in Figs. 1 to 4 inclusive. Instead of the toothed pawl 60 shown in Fig. 60 3, the form of apparatus at present being described includes a toothed rack 60^a mount- 65

ed in a suitable recess 60^b, formed in the auxiliary member 54^c and normally occupying the position illustrated in Fig. 14; a spring 60^c is located between one end of the rack 60^a and a wall of the recess 60^b. A catch 60^d is pivotally mounted at 60^e upon the member 54^c and is constructed with a catch member 60^f which is arranged to extend into the recess 60^b beyond the one end of the rack 60^a for maintaining the latter in the position illustrated in Fig. 16, a coil spring 60^g tending to press the catch member 60^f, at all times, toward the rack 60^a. The catch 60^d is further provided with a recess 60^h in which a bolt 60ⁱ is slidably mounted, said bolt being provided with a handle 60^j extending through a slot 60^k in the catch 60^d for convenience of manipulation. The bolt 60ⁱ is movable to an operative position beyond the one end of the rack 60^a for maintaining the latter in an inoperative position, as shown in Fig. 15, for the purpose to be more fully described hereinafter. The catch 60^d, in addition to its other functions, takes the place of the tripping member 50 of the first form 90 and at the proper time trips the trigger 49 to release the latch bolt 44 and is itself actuated by engagement with said trigger, to release the toothed rack 60^a, as will be more fully described hereinafter. In addition to the parts so far described, the present form of my invention includes a locking device which, in its illustrated form, comprises a support 67 secured upon the member 54^a and provided with an internal guideway in 95 which a locking member 68 is slidably mounted and adjusted to and from an operative position by means of a screw 69 provided with an operating head 70 located exteriorly of the support 67. It will be understood that while the screw is freely rotatable relatively to the support 67, it is held against lengthwise movement relatively thereto by means of flanges 71 and 72 located, as illustrated in Fig. 14. To facilitate the operation of the mechanism, this form of my apparatus may also be provided with an operating handle 66 secured upon the member 54^a. 100 For convenience of description, it will be assumed that this second form of my dividing head is being used also for the purpose of cutting gears upon a blank or, in other words, to be specific, for cutting one hundred teeth upon the periphery of the blank in question. It will be understood 105 that in this case also, this is only an example and that the device may be otherwise used and that the gear teeth referred to are to be taken merely as representative of divisions into which the blank may be divided automatically and efficiently with the aid of the apparatus herein described. To bring about the proposed result, the arm 36, if not already in such 110 position, is first adjusted as previously de- 115

70

scribed, to bring the locating pin into registry with the first aperture 43^a of the series a into which said locating pin is snapped. It will be understood that in this condition, the parts are locked together as shown in Fig. 13. In order to properly set the apparatus for the operation suggested above, the handle 66 is swung to the right in Fig. 14 until the cam 56 passes over and beyond the latch member 44 and depresses the same out of engagement with the teeth 43, the described movement being continued until the indicating line α which may be produced upon the face of the index plate 42 a is in registry with the latch member 44. The latter is then tripped by manually actuating the trigger 49 and by re-engagement with the teeth 43 locks the parts in the adjusted position. The members 54 a and 54 c are now released from each other by a proper actuation of the screws 54 d whereby the member 54 a is free to move relatively to the member 54 c in either direction and also to the index plate 42 a , the bolt 60 c having previously been adjusted to maintain the rack 60 a in the inoperative position shown in Fig. 15. This arrangement is provided in order to permit the member 54 a to be freely and independently actuated in either direction. If the rack is permitted to remain in engagement with the ratchet 63 a , the member 54 a is independently movable only in one direction and under certain conditions may have to make a complete circuit to attain the desired adjustment. At this stage, the handle 66 is moved in a return direction or to the left in Fig. 14 until the locking device 68 is in registry with the indicating line α whereupon the locking member 68 is moved into engagement with the toothed periphery 43 and thereby locks the member 54 a against independent rotative movement. The member 54 c is now rotated relatively to the member 54 a and ratchet wheel 63 a through the medium of the catch 60 d until the latter engages the trigger 49 but does not trip the same. After this adjustment has been effected, the locking member 68 is released from the teeth 43 and the member 54 a is rotatably shifted to a position in which the locking member registers with a predetermined tooth 43. For instance, if the work is to be divided into a hundred equal divisions or, in other words, a hundred gear teeth are to be cut, as hereinbefore suggested, the locking member 68 is brought into registry with the space between the third and fourth teeth, counting from the space which registers with the indicating line. As soon as this has been done, the screws 54 d are manipulated to lock the members 54 a and 54 c together, after which the operation of the dividing head may be proceeded with, it

being understood that the locking member 68 is first moved to an inoperative position out of engagement with the teeth 43, as indicated in Fig. 14. As the handle 66 is now actuated toward the right in Fig. 14, the members 54 a and 54 c will partake of this movement as a unit and will carry along the cam 56 and also the projection 64 a ; the rack 60 a , during this movement, is retarded by the ratchet 63 a and is shifted thereby from the position shown in Fig. 14 to the position shown in Fig. 16 in which it is locked by the catch member 60 c and in which it is in operative engagement with said ratchet 63 a . This relative movement between the rack and ratchet or lost motion, as it may be termed, is just sufficient to move the lift cam 56 the necessary distance required to depress the latch member 44 out of engagement with the teeth 43. A continued rotation of the members 54 a and 54 c through the medium of a continued actuation of the handle 66 in the indicated direction will now rotate the ratchet 63 a and with it the index plate 42 a which, by reason of its connection through the medium of the locating pin 39 with the carrier 33 and consequently with the spindle 18 brings about a corresponding rotation of the latter and with it the work or blank which is mounted thereon. As soon as the described operation of the parts is sufficient to bring the catch 60 c into engagement with the trigger 49, the latter is tripped and releases the latch member 44, which again snaps into engagement with the teeth 43 and locks the index plate 42 a and ratchet 63 a and with them the spindle 18 and the work carried thereby against further rotation and against rotation in a return direction. At the same time, this engagement of the trigger 49 by the catch 60 c swings the latter against the tension of the spring 60 e and thus releases the rack 60 a which drops to an inoperative position and thereby releases the ratchet 63 a . A movement of the handle 66 in the reverse direction or toward the left in Fig. 14 will now rotate the members 54 a and 54 c as a unit relatively to the ratchet 63 a , index plate 42 a , spindle 18 and the work carried thereby, the rack 60 a , cam 56 and projection 64 a partaking of this return movement. This return movement is continued until the projection 64 a abuts against the housing 45, whereupon the handle 66 is again manipulated to the right in Fig. 14 to again actuate the parts as previously described and to bring the work to a new position for the second division or, in the present example, the cutting of the second gear tooth. These operations of the handle 66 are continued alternately five times in the example chosen for the purpose of illustration, whereby a complete rotation of the blank has been ac-

complished and twenty teeth have been cut thereon or said work has been adjusted to successive positions for the production thereon of twenty divisions. The locating pin is now withdrawn from the first aperture of the series *a* and moved to a position in which it registers with the second aperture of this series to readjust the parts in the same manner as previously described, 10 this operation being repeated each time a complete rotation of the blank has been had and twenty additional teeth have been cut thereon or twenty additional divisions produced thereon, as the case may be. In the 15 present instance, therefore, in which a hundred teeth or a hundred divisions are being cut or produced upon the blank, the operation provides for the adjusting of the blank to five different positions in each of 20 which twenty teeth are cut or twenty divisions are produced in exactly the same way as described with respect to the form first referred to herein.

To cut the teeth in numbers not provided for upon a given index plate or to divide a blank otherwise than provided for on said index plate, it is simply necessary to substitute another index plate of the proper kind and then proceed as before. 25 The index plate, regardless of its arrangement serves, in cooperation with the pin 39 and arm 36, to maintain the parts of the mechanism and the work in their adjusted relations. From the foregoing, it will be 30 seen that the arm 36 serves at the proper time to shift the work or blank in successive stages to a series of predetermined positions, each having a starting point advanced with respect to that of the preceding stage so that the handle 36 and its 35 correlated parts actuate the work or blank in successive steps in each stage to bring it to a series of positions in which the teeth may be cut or divisions or other devices produced successively upon the blank.

The apparatus is extremely simple in construction and of maximum efficiency and operation and requires no skilled attention in its manipulation. It is particularly 50 adapted for use in combination with a milling machine to adjust the work for the purpose of equally and accurately dividing the same in any predetermined manner and for any purpose such as gear cutting, graduating and, in fact, in any case where a circle, 55 in the form of work, is to be divided. The operative movements required to actuate the device are continuous in a given direction and require no special thought on the 60 part of the operator to be successfully carried out. In the illustrated examples, and more particularly in the form shown in Figs. 13 to 17, these movements must be 65 carried to completion in each instance before another movement may be started; the

device, as a result, is very accurate and constant in its functions and may be operated at high speed.

It will be understood that the clutch arrangement illustrated may be replaced by other forms and types of devices for holding and supporting the work. 70

Various changes in the specific form shown and described may be made within the scope of the claims without departing 75 from the spirit of my invention.

I claim:

1. A dividing head comprising rotatable means for supporting the work, actuating means for rotating said rotatable means in successive stages, each of which includes successive steps corresponding to predetermined divisions of the periphery of the work and means for adjusting the position of the work with respect to said actuating means to rotatably advance each successive stage with respect to the preceding one. 85

2. A dividing head comprising a headstock, a shaft journalled therein, means on said shaft for supporting thereon the blank to be divided, actuating mechanism loosely mounted on said shaft and arranged to be rocked thereon, means for coupling said mechanism to said shaft and for rotatably adjusting the latter relatively thereto to 90 rotatably advance the blank, and means for locking said coupling means and shaft against rotation during a movement of recovery of said actuating mechanism. 95

3. A dividing head comprising a headstock, a shaft journalled therein, means on said shaft for supporting thereon the blank to be divided, an actuating member arranged to be rocked relatively to said shaft, means for coupling said shaft to said member during a movement of the latter in an operative direction, a device for rotatably adjusting said shaft with respect to said member to rotatably shift the blank to new positions, an index member rotatable relatively to said shaft and fixing said device in an adjusted position, means for locking said index member against rotation during the adjustment of said device and during a movement of the actuating member in a return direction and means for releasing said locking means to permit said index member to move with said shaft during the operative movement of said actuating member. 100 105 110 115

4. A dividing head comprising a headstock, a shaft journalled therin, an actuating member loosely mounted on said shaft, a ratchet wheel fixed on said shaft, a pawl carried by said member whereby the latter is operatively connected to said ratchet and thereby coupled to said shaft, said pawl having a predetermined movement relatively to said ratchet wheel prior to becoming locked therewith, whereby said actuating member is capable of an initial 120 125 130

movement independent of said shaft, a toothed index plate loosely mounted on said shaft and having apertures located in groups upon a face thereof, a spring-pressed latch-pin 5 co-operating with said teeth to lock said index plate against rotation, an arm fixed upon said shaft and adapted to rotatably adjust the latter with respect to said actuating member, a spring-pressed locating pin 10 co-operating with said apertures to lock said arm in an adjusted position, a pivoted cam member carried by said actuating member for releasing said latch-pin from the teeth of said index plate during said initial independent 15 movement of said actuating member, a trigger for maintaining said latch-pin in its inoperative position and a tripping member carried by said actuating member and adjustable toward and away from said 20 cam to trip said trigger and permit said latch-pin to re-engage said teeth.

5. A dividing head comprising a head-stock, a shape journalled therein and arranged to carry the work to be divided, a 25 ratchet wheel loosely mounted upon said shaft and having a hub, an index plate secured to said ratchet to move therewith, actuating means loosely mounted upon the hub of said ratchet wheel, a rack slidably 30 mounted upon said actuating means for cooperation with said ratchet wheel, a device for rotatably adjusting said shaft with respect to said ratchet wheel and index plate to shift the work to new positions, said device 35 cooperating with said index plate to fix the parts in an adjusted relation, means for locking said index plate against rotation during the adjustment of the device and during a movement of the actuating means 40 in a return direction and means for releasing said locking means to permit said index plate and ratchet wheel to move with said shaft by means of said pawl during the operative movement of said actuating 45 means.

6. A dividing head comprising a head-stock, a shaft journalled therein, a ratchet wheel loosely mounted on said shaft, actuating means rotatable relatively to said 50 ratchet wheel, a pawl rack slidably carried by said actuating means whereby the latter is operatively connected to said ratchet, said pawl rack having a predetermined movement relatively to said ratchet wheel prior 55 to becoming locked therewith, whereby said actuating means is capable of an initial movement independent of said ratchet wheel,

a toothed index plate connected with said ratchet wheel to move therewith and having apertures located in groups upon a face 60 thereof, a spring-pressed latch-pin co-operating with said teeth to lock said index plate against rotation, an arm fixed upon said shaft and adapted to rotatably adjust the latter with respect to said actuating 65 means, a spring-pressed locating pin co-operating with said apertures to lock said arm in an adjusted position, a pivoted cam member carried by said actuating means for releasing said latch-pin from the teeth of 70 said index plate during said initial independent movement of said actuating means, a trigger for maintaining said latch-pin in its inoperative position and a tripping device carried by said actuating means whereby 75 said pawl rack is locked in engagement with said ratchet wheel and whereby said trigger is tripped to permit said latch-pin to re-engage said teeth.

7. A dividing head comprising a head-stock, a shaft journalled therein, means on said shaft for supporting thereon the blank to be divided, a two-part actuating member mounted to rock relatively to said shaft, means whereby the two parts of said actuating member are locked together, a combined ratchet wheel and index member 80 loosely mounted on said shaft, a pawl for connecting said actuating member and said ratchet wheel, a device for rotatably adjusting said shaft with respect to said index member to rotatably shift the blank to new 85 positions, and cooperating with said index member to fix said device in an adjusted position, means for locking said index member 90 against rotation during the adjustment of said device and during a movement of the actuating member in a return direction, means carried by one part of said actuating member for shifting said locking member to 95 an inoperative position to permit said index to move with said shaft during the operative movement of said actuating member, and means carried by the other part of said actuating member and acting as a lock for maintaining said pawl in connection with said ratchet wheel and as a trip to release said locking member from its inoperative position and being itself concurrently tripped to 100 release said pawl.

In testimony whereof I have hereunto set my hand.

JOSEPH A. POITRAS.
